UNITED STATES PATENT OFFICE

HERMAN P. RUF, OF NEW YORK, N. Y.

CORD MACHINE

Application filed September 30, 1927. Serial No. 223,101.

This invention relates to textile machinery and has particular reference to covered cord making machines and particularly machines intended for the silk coating of cords having a core of cotton or other relatively cheap material.

One object of this invention is to provide an improved machine of the character set forth having a plurality of fliers or cord making units, and associated means for adjusting the nature of the cord or twisted product produced by a flier, such adjustment being independent of the other fliers, so that the same machine may make a number of cords of varying types.

A further object of the invention is to provide a machine of the character set forth having improved drive means, so that the operation of the machine is greatly simplified, and a plurality of cords produced which may be twisted in opposite directions. A further object of the invention is to provide a machine of the character described having comparatively few and simple parts, co-ordinated for operation in an efficient manner.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a front elevation of a machine embodying the invention, but with one of the fliers or cord making units removed.

Fig. 2 is an enlarged sectional view taken approximately on the line 2—2 of Fig. 1, but with parts broken away.

Fig. 3 is a fragmentary detail view taken on the line 3—3 of Fig. 2.

Fig. 4 is a side elevation of the device shown in Fig. 3.

Fig. 5 is a fragmentary detail view of the belt drive.

Referring in detail to the drawings, 10 denotes a machine embodying the invention, and

constituting an improvement over the machine shown in my co-pending application, Serial No. 139,569, filed October 5th, 1926.

Said machine comprises a frame 10^a having a plurality of cross members 10^b, 10^c, 10^d, and 10^e which not only serve to strengthen the frame, but also serve as supports for the various parts of the operating mechanism. At the top of the frame, a plurality of guide members 11 are provided on bars 12 to guide the core portion 13 of the cord down toward the several fliers or cord making units. The cover threads 14 for the manufactured product of the machine are directed toward the cord making units by the guides 15 and over the horizontal bars 16.

A plurality of cord making units 17 are employed, which are all preferably exactly alike, but are nevertheless so constructed as to be adjustable so that each may produce a different cord than the other. Each unit 17 includes a central quill 18 through which the core 13 passes, and a guide plate 19 having holes 19^a for the silk threads 14, said plate being mounted on the quill, and the silk threads passing from said guide plate downward along the elements of a conical member 20. At the end of the conical member the silk threads are twisted about the core.

Each cord making unit includes a flier 21 coaxial with a corresponding quill 18. Each of the fliers has a head 21^a, a pair of vertical arms 21^b, and guiding rollers 21^c disposed on said arms. To rotate the fliers, pulleys 22 are provided coaxial therewith. Each of the pulleys 22 is fixed to a sleeve 23 which is journaled for rotation at a reduced portion 23^a thereof by means of a bearing 24 in the cross bar 10^e of the machine frame, the bearing being preferably re-enforced by a supporting plate 25^b bolted to the lower side of said cross bar. It is thus seen that the bearing 24 is well able to sustain the weight of the flier 21 which is secured to the reduced portion 23^a of the sleeve 23 by means of a set screw 26 in the head 21^a of the flier. Since the pulleys 22 are all preferably of the same size, and are rotated at the same speed, as will be described hereinafter, it is clear that the different fliers will all turn at the same speed.

A central drive is arranged for all the fliers, said drive including loose and tight pulleys 25 and 25^a, the latter driving a coaxial pulley 25^c, over which passes a belt 25^d that engages 5 a pulley 27. The latter is secured to a shaft 28 upon which are mounted pulleys 29. Belts 30 engage the pulleys 29 and the pulleys 22. The construction is such that the belts 30 must each be as shown. An important advantage results in that a belt can be disposed 10 in one way or in another so that one flier can be rotated in one direction, and another flier in an opposite direction to make cords having twists in different directions.

15 In Fig. 5 is shown a detail of this improved drive arrangement. It is noted that the central plane *a* of pulley 29 is tangent to pulley 22, which is a necessary feature. Should it be desired to reverse the drive, the pulley 29 20 will be shifted along shaft 28 until the central plane of said pulley is tangent at *b* to the pulley 22, and the belt 30 is then twisted in opposite direction.

25 Each cord making unit includes means to permit the twist of the cord to be regulated independently of any other unit. Thus a plurality of rollers 31 are mounted on each flier head, said rollers being rotated by their coaxial gears 32. The gears 32 mesh with a 30 gear 33 that is coaxial with the flier. The gear 33 is driven by any suitable friction drive that permits of speed adjustment so that the cord C wound on the rollers 31 is drawn through the cord making unit at any desired 35 velocity. It is clear that if the rate at which the cord is drawn through is high, that the twist on said cord will not be so tight as it would be if, for instance, the cord is drawn at a low rate.

40 The gear 33 is mounted on a quill or guide 34 for the cord C coaxial with the flier and positioned within the sleeve 23 for independent rotation by means of an improved friction drive 35. The drive 35 includes a pair of 45 coaxial members 36 and 37 having bell shaped outer surfaces with their circumferential concavities facing one another. The member 36 is secured to sleeve 23, while the member 37 is mounted on the quill 34 to rotate the same. The members 36 and 37 are arranged to be in 50 predetermined proximity or spaced relation to one another, the quill 34 being supportingly mounted in a bearing 38 in the cross bar 10^b of the machine frame.

55 To make the rotation of the member 36 effective to the member 37, a pair of wheels 39 and 40 are coaxially mounted on the ends of a shaft 41 to rotate at the same speed. Said shaft 41 is supported in endwise slidable relation in a bearing 42. The bearing 42 is supported on a frame 43 that is pivotally mounted on a shaft 44 that is supported on a bracket 45. Springs 46 acting between the frame 43 and the cross bar 10^b draw the wheels 60 39 and 40 strongly in contact respectively

with the members 36 and 37. The bearing 42 is itself mounted on stub shafts 46 and 47 which are parallel to the shaft 44 and extend transversely to the shaft 41. To the stub shaft 47 is secured an arm 48, and said stub shaft 47 is secured to the bearing 42 by means of a set screw 49. A screw 50 journaled in a lug 51 wherein it is retained against endwise movement by a set screw 52 engaging in a groove 53, has threaded engagement with a 70 thimble 54 journaled in the end of the arm 48. Thus on turning screw 50 by means of the handle 55 thereof, the arm 48 is caused to move pivotally so as to swing the wheels 39 and 40 bodily about the axis of the stub shafts 80 46 and 47. Since the wheels make reliable contact by means of friction rings 56 with the members 36 and 37, it follows that when such bodily pivotal movement of wheels 39 and 40 occurs, that the relative sizes of the 85 circumferences gripped by the wheels will vary so that member 37 will turn at a different speed than member 36. This in turn will cause gear 33 to rotate at any desired different speed than the flier so that the rollers 31 90 will rotate to draw the cord C through the cord making unit at the required rate to produce the desired twist. It is thus seen that conditions in each flier may in this respect be varied to produce different kinds of cord C. 95

The cord C is wound by the flier on a spool 58 which is mounted on a vertical rod 59 that is supported on a horizontal bar 60. Said bar 60 is secured on vertically slidable rods 61 having followers 62 actuated by cams 63 100 to raise and lower the spools 58 so that the cord is wound uniformly thereon. A suitable gear train 68 is provided that is operated by shaft 64 rotated by pulley 25^a to actuate said cams. To frictionally retard the spools 58 so that the cord will be wound snugly, a weight 65 is suspended on a cord 66 which runs in a groove of a wheel 67 that is freely rotatable about a rod 59 and acts as a washer between each spool and the bar 60. 110

I claim:

1. In a machine of the character set forth, a cord making unit to make twisted cord, and means to adjust the speed at which the cord is produced by the unit, said means including rollers to draw the cord through the unit, means to rotate the rollers, and a friction drive to rotate the last mentioned means, said friction drive including a pair of coaxial bell shaped members having their circumferential concave surfaces facing each other, a pair of coaxial wheels contacting said members, said wheels being mounted on a shaft so that rotation of one of the members will cause the wheels and in turn the other member to rotate, means pivotally supporting said shaft on an axis transverse to the shaft to shift the lines of contact of the wheels and said members, a spring tending to move the shaft toward the members for snug contact with the wheels, 120 125 130

means to set said shaft in desired pivoted position and a hollow quill for the cord, said quill extending centrally through both bell shaped members.

- 5 2. In a machine of the character set forth, a cord making unit to make twisted cord, and means to adjust the speed at which the cord is produced by the unit, said means including rollers to draw the cord through the unit, 10 means to rotate the rollers, and a friction drive to rotate the last mentioned means, said friction drive including a pair of coaxial bell shaped members having their circumferential concave surfaces facing each other, a pair of 15 coaxial wheels contacting said members, said wheels being mounted on a shaft so that rotation of one of the members will cause the wheels and in turn the other member to rotate, means pivotally supporting said shaft on an 20 axis transverse to the shaft to shift the lines of contact of the wheels and said members, and means to set said shaft in desired pivoted position, a pulley being connected to one of said members, a belt drive being provided to 25 rotate the pulley and a quill for the cord extending centrally through said pulley and said member, said quill being connected at one end to the other member and at its other end to the means to rotate the rollers.
- 30 3. In a machine of the character set forth, a cord making unit to make twisted cord, and means to adjust the speed at which the cord is produced by the unit, said means including rollers to draw the cord through the unit, 35 means to rotate the rollers, and a friction drive to rotate the last mentioned means, said friction drive including a pair of coaxial bell shaped members having their circumferential concave surfaces facing each other, a pair of 40 coaxial wheels contacting said members, said wheels being mounted on a shaft so that rotation of one of the members will cause the wheels and in turn the other member to rotate, means pivotally supporting said shaft 45 on an axis transverse to the shaft to shift the lines of contact of the wheels and said members, means to set said shaft in desired pivoted position, a drive connected to one of the members, and a quill for the cord centrally 50 connected at one end to the other member and at its other end to the means to rotate the rollers, the member connected to the drive being journaled on the quill intermediate the ends of the latter.

- 55 4. In a machine of the character set forth, a frame, a cord making unit to make a twisted cord, a concentric rotatable quill journaled at one end thereof in the frame, said quill receiving the cord and within which it is 60 twisted, a flier alined with the unit, rollers to draw the cord through the said unit, said quill being connected to rotate the rollers, a sleeve journaled in the frame remote from the point at which the quill is journaled, said quill 65 being within the sleeve and journaled therein,

said sleeve being connected to rotate the flier, and an adjustable drive acting between said sleeve and said quill to impart rotation to the latter at any desired speed with respect to the flier, said adjustable drive including a pair of coaxial bell shaped members having their circumferential concave surfaces facing each other, a pair of coaxial wheels contacting said members, said wheels being mounted on a shaft so that the rotation of one of the members will cause the wheels and in turn the other member to rotate, means pivotally supporting said shaft on an axis transverse to the shaft to shift the lines of contact of the wheels and said members, and means to set said shaft in desired pivoted position, one of the members being connected to the quill and the other to the sleeve.

In testimony whereof I affix my signature.
